MACHINE FOR CEMENTING PATCHES ON
SHOE SOLES

Harry R. Myers, Zanesville, Ohio

Application April 10, 1937, Serial No. 136,193

7 Claims. (Cl. 12—33)

This invention relates to shoe repairing machines and more particularly to a machine especially designed for applying patches or taps to shoe soles.

5 The object of the invention is to provide a shoe repairing machine of simple and inexpensive construction by means of which patches or taps may be cemented to the toe or other portion of a shoe sole with greater facility and more economically than heretofore.

A further object of the invention is to provide a shoe repairing machine including an anvil or support and a vertically movable shoe holder coating therewith for applying pressure to the 15 tap or patch during the cementing operation, said anvil or support having a heating unit housed therein to insure rapid drying of the cement and thus expedite application of the patch to a shoe sole.

20 A further object is to provide a shoe repairing machine comprising a standard having an overhanging stationary head formed with an angular slot and on which is mounted for lateral swinging movement a pivoted block constituting a guide 25 for the plunger of the shoe supporting element, there being an operating lever pivotally mounted on the guide block and operatively connected with said plunger whereby, after pressure on the patch has been effected, an initial movement imparted to the lever will elevate the shoe supporting element above the anvil and a further movement thereof swing the guide block carrying the plunger and supporting element laterally of the machine so as to permit convenient removal of 30 the repaired shoe from said supporting element.

A still further object of the invention is generally to improve this class of machines so as to increase their utility, durability and efficiency.

Further objects and advantages will appear in 40 the course of the following specification.

In the accompanying drawings forming a part of this specification and in which similar numerals of reference indicate corresponding parts in all the figures of the drawings:

45 Figure 1 is a side elevation, partly in section, of a shoe repairing machine embodying the present invention.

Figure 2 is a horizontal sectional view taken on the line 2—2 of Figure 1.

50 Figure 3 is a vertical sectional view taken on the line 3—3 of Figure 1.

Figure 4 is an enlarged detail side elevation showing the position of the shoe supporting element and its associated parts when the operat-

ing lever has reached the end of its downward movement,

Figure 5 is a perspective view of the stationary slotted head, guide block and a portion of the plunger detached,

Figure 6 is a transverse sectional view taken on the line 6—6 of Figure 4, and

Figure 7 is a detail vertical sectional view illustrating a modified form of heating unit.

The improved shoe repairing machine forming 10 the subject-matter of the present invention comprises a base 5 having a standard 6 arising therefrom and provided with laterally extending arms 7, to each of which is rigidly secured or formed integral therewith an enlarged stationary head 8. 15 Any desired number of repair units may be mounted on the base 5, two complete units being shown in the present instance, and as said units are identical in construction a detailed description of one will suffice. The head 8 of each repair unit is provided with a smooth flat outer face 9, and opening through the bottom of the head is a slot 10 provided with an angular extension 11, the purpose of which will be referred to hereinafter. Pivotaly mounted on the flat outer face 9 of the head 8 by means of a screw or pin 12 is a guide block 13 having a dove-tail channel 14 formed in the outer face thereof and in which is slidably mounted for reciprocating movement a correspondingly shaped plunger 15. A vertical slot 16 20 is formed in the wall of the channel 14 and opens through the bottom of the block, as best shown in Figure 5 of the drawings, and this slot 16 normally registers with the slot 10 in the enlarged head 8 to permit the passage of a pin 17 extending 25 laterally from the plunger. The lower end of the plunger 15 is provided with a reduced extension 18 to which is detachably secured a shoe supporting element 19. The upper portion of the shoe supporting element 19 is provided with a socket 20 30 to receive the extension 18 of the plunger and communicating with said socket is a slot 21 defining spaced ears 22 through which extends a bolt or similar fastening device 23, by means of which the shoe supporting element may be detachably 35 secured to the extension of the plunger. The intermediate portion of the shoe supporting element 19 is preferably curved laterally while the free end thereof carries a toe plate 24 adapted to fit within a shoe, indicated at S. The lower 40 end of the shoe supporting element is formed with a slot 25 adapted to receive a bolt or other suitable fastening device 26 so as to permit the attachment of toe plates of different sizes and shapes according to the kind of repair work to be 45

50

55

performed. Disposed beneath the plunger 15 is a combined support and heating unit 27, said support comprising a tubular body 28 preferably formed integral with the base 5 and having its upper end open and normally closed by a removable top or cover plate 29. The cover plate 29 is provided with a circumferential retaining flange 30 which receives and holds a pad 31 formed of rubber or other yieldable material. Disposed 5 within the tubular body 28 is a heating unit preferably in the form of an electric bulb 32, the lower end of which is detachably fitted in a standard socket 33 connected in a lighting circuit 33' including a switch 33'', as shown, and the purpose 10 of the heating unit is to hasten the drying action of the cement when applying a patch to the sole of a shoe.

Pivottally mounted at 34 on one side of the guide block 13 is an operating lever 35, the pivoted end of which is formed with an angular extension 36 to which is pivottally connected, at 37, one end of a connecting link 38, the opposite end of which is pivottally connected, at 39, to the adjacent portion of the plunger 15. A suitable stop or rest 40 is secured to one side of the guide block 13 and on which the adjacent portion of the operating lever rests when the plunger is in lowered position.

In operation, the toe or other portion of the 30 shoe S to be repaired is first skived or beveled in the usual manner to receive the patch P, after which said patch is coated with cement or other suitable adhesive and applied to the treated portion of the shoe sole. Assuming the 35 parts to be in the position shown in Figure 4 of the drawings, the shoe with the patch in position thereon is placed on the supporting element 19 and the lever 35 swung upwardly and laterally, thereby bringing the supporting element 19 with the shoe in position thereon directly above and over the support or anvil 27. With the parts in this position, the pin 17 will aline with the slots 10 and 16 and, by pressing downwardly on the 40 lever 35 until it engages the stop 40, the link 38 will force the plunger downwardly so as to cause the toe plate 24 to press the patch against the rubber pad of the anvil and in which position it will be held until the heating unit 32 thoroughly dries the cement. The rubber pad 31 45 equalizes the pressure on the pad so as to cause the patch to conform to any irregularities in the surface of the shoe and thus produce a neat job. It will here be noted that, when the lever 35 is in contact with the stop 40, the pivots 34, 37 and 39 will be in alinement with each other so as to lock the supporting arm in pressing position. After the patch has been cemented on the shoe sole, the lever 35 is swung upwardly, thereby elevating the plunger and shoe supporting element 50 and this elevation of the plunger is continued until the end of the pin 17 reaches the upper end of the slot 10 when a further pressure on the lever will cause the pin 17 to ride in the lateral slot 11 of the head 3, thereby swinging the guide block 13 and its associated parts laterally until swinging movement of the block is arrested by engagement of the pin 17 with the end wall of the slot 11. This swinging movement of the guide block causes the shoe supporting element 19 to assume the position shown in Figure 4 of the drawings and in which position the shoe may be readily removed from the toe plate.

In Figure 7 of the drawings, I have shown a modified form of heating unit. In this form of 75 the device instead of employing an incandescent

lamp, I make the support or anvil 41 shorter and place in the bottom thereof a resistance coil 42 of any suitable construction. It is preferred, however, to use an electric light bulb as the heating unit as by so doing the electric bulb 5 may be readily removed and replaced by a new bulb whenever necessary by simply detaching the cover plate 29 and unscrewing the bulb from the socket 33, as will be readily understood.

From the foregoing description, it is thought that the construction and operation of the device will be readily understood by those skilled in the art and further description thereof is deemed unnecessary.

Having thus described the invention, what is 15 claimed as new is:

1. A machine of the class described comprising a standard, a stationary slotted head carried by the standard, a slotted guide block pivottally mounted on the head, a plunger movable vertically within the guide block, a shoe supporting element carried by the plunger, a support disposed beneath the shoe supporting element, a pin carried by the plunger and extending through the slots in the guide block and head 20 respectively, and a lever operatively connected with the plunger for pressing the supporting element 25 and a shoe carried thereby against the support to cement a patch on said shoe.

2. A machine of the class described comprising a standard, a stationary head carried by the standard and provided with a substantially L-shaped slot, a guide block pivottally mounted on the head and having a slot adapted to register with a portion of the L-shaped slot, a plunger 30 mounted for vertical movement in the guide block, a shoe supporting element carried by the plunger, a support disposed beneath the shoe supporting element, a heating unit housed within the support, means for pressing the shoe supporting element and a shoe thereon against the support to cement a patch on said shoe, and means for moving the supporting element laterally to permit removal of a shoe therefrom.

3. A machine of the class described comprising a standard having an overhanging arm, a stationary head carried by the arm and provided with an angularly disposed slot, a block pivottally mounted on the head and provided with a guide channel and having a slot opening through the lower end of the channel, a plunger slidably mounted in the guide channel, a pin projecting laterally from the plunger and extending through the slots in the block and head respectively, a shoe supporting element carried by the plunger, 50 a support, means for heating the support, and an operating lever connected with the plunger and adapted when moved in one direction to press the shoe supporting element and a shoe thereon against the support to cement a patch 55 on said shoe and when moved in another direction to swing the shoe supporting element laterally to one side of the support to permit removal of the shoe from the supporting element.

4. A machine of the class described comprising a standard, a stationary slotted head carried by the standard, a support, a slotted guide block pivottally mounted on the head, a plunger operating within the guide block, a pin carried by the plunger and fitting within the slots of the 60 guide block and head respectively, a shoe supporting element carried by the plunger, an operating lever pivottally mounted on the guide block, and a link connection between the pivoted end of the lever and the plunger whereby when the lever is 65 70 75

removed in one direction the shoe supporting element and a shoe thereon will be forced against the support to cement a patch on said shoe and when moved in the opposite direction the shoe supporting element will be swung laterally to one side of the support to permit the removal of a shoe therefrom.

5. A machine of the class described comprising a base, a standard arising from the base and provided with an overhanging arm, a stationary head carried by the arm and provided with a substantially L-shaped slot, a guide block pivotally mounted on the head and provided with a slot adapted to register with the slot in the head, a plunger slidably mounted in the guide block, a pin extending laterally from the plunger and fitting within the slots of the guide block and head respectively, a shoe supporting element carried by the plunger, a support disposed beneath the supporting element, means for heating the support, an operating lever pivotally mounted on the guide block and provided with a bell crank extension, and a link connection between the bell crank extension of the lever and said plunger whereby when the operating lever is moved in one direction the shoe supporting element and a shoe thereon will be pressed against the support and when moved in another direction the guide block and shoe supporting element 15 will be moved laterally to one side of the support, the end of the pin on the plunger by engagement with the end wall of the slot in the stationary head serving to limit the lateral swinging movement of said shoe supporting element.

6. A machine of the class described comprising a base, a standard arising from the base, a support resting on the base, means for heating the support, a stationary slotted head carried by the standard, a guide block pivotally mounted 5 on the head and provided with a vertical slot opening through the bottom thereof and adapted to register with the slot in the head, a plunger slidably mounted in the guide block, a shoe supporting element carried by the plunger, an operating lever pivotally mounted on one side of the guide block, a rest for the handle disposed on the opposite side of the guide block, and a link connection between the operating handle and said plunger.

10. 7. A machine of the class described comprising a standard having a slotted portion, a support, a slotted guide block pivotally mounted on the standard, a plunger operating within the guide block, a pin carried by the plunger and fitting within the slots of the guide block and standard respectively, a shoe supporting element carried by the plunger, an operating lever pivotally mounted on the guide block, and a link connection between the pivoted end of the lever 20 and the plunger whereby when the lever is moved in one direction the shoe supporting element and a shoe thereon will be locked against the support to cement a patch on said shoe and when moved in the opposite direction the shoe supporting element will be swung laterally to one side of the support to permit the removal of a shoe 25 therefrom.
